(57) **CLAIM**

The ornamental design for a papermaking belt and product produced therefor, as shown and described.

DESCRIPTION

The sole FIGURE is a top plan view of a papermaking belt and product produced therefor showing our new design.

The broken lines shown along the border of the FIGURE depict the boundaries of one repeat unit of the claimed design and indicate that the design may continue indeterminately in one or more directions. The broken lines form no part of the claimed design.
